FUSE AND IGNITER

Gustaf W. Hammar, Moscow, Idaho, George A. Noddin, Wenonah, N. J., and Donald E. Rosen, Takoma Park, and Frank J. Trelease, Oxford, Md., assignors to the United States of America as represented by the Secretary of the Navy

Application December 29, 1945, Serial No. 638,390

3 Claims. (Cl. 102—7)

1

This invention relates to a delayed action fuse which is activated by mechanical means. Further, it relates to a delayed action fuse of the powder train type which is activated by a trigger tripping mechanism; and in particular it relates to an assembly of a delayed action fuse which is activated by a trigger tripping mechanism, which (assembly) is adapted for subaqueous operation.

Delayed action time fuses which depend upon the length of the powder train for their timing function and mechanically tripped triggers which detonate primers are both known. But in general these are not adapted to function under water nor to operate efficiently under the severe conditions which this invention efficiently meets. This invention functions under certain conditions of time, interior pressure, external pressure, temperature and under water.

It is, therefore, the general object of this invention to provide apparatus adapted to function under the above stated conditions and more specifically;

It is an object of this invention to provide a mechanically activated fuse for such apparatus the igniting action of which is delayed from 5 to 6 seconds.

It is also an object of this invention to provide an assembly of a mechanically activated fuse therefor, the structure of which will withstand an external pressure of 200 lbs. per square inch and an internal pressure of 1000 lbs. per square inch.

It is a further object of the invention to provide an assembly of a mechanically activated fuse the structure of which is capable of withstanding a gas at high temperature in contact with its inner surfaces while its outer surfaces are in contact with water at meteorological temperatures.

It is still a further object of this invention to provide a mechanically activated fuse which is capable of igniting in an enclosed space black powder at a distance of three inches and trench mortar sheet powder at a distance of one inch.

It is an additional object of the invention to provide an assembly of a mechanically activated fuse structure which is sufficiently strong and durable to meet the above objectives, but which is relatively light in weight and capable of efficient manufacture.

With these objectives in view reference is now made to the drawings which are illustrative of a preferred embodiment of the invention, and in which:

Figure 1 is a vertical transverse section through

2

the trigger tripping mechanism of the apparatus of the present invention, partly in elevation, taken along section line 1—1 of Figure 2 in the direction indicated by the arrows;

Figure 2 is a vertical longitudinal section through the trigger tripping mechanism and associated structure, partly in elevation, taken along line 2—2 of Figure 1 in the direction indicated by the arrows;

Figure 3 is a vertical longitudinal section through the delayed action fuse, partly in elevation, taken along line 3—3 of Figure 5 in the direction indicated by the arrows;

Figure 4 is a horizontal longitudinal section, partly in elevation, taken along line 4—4 of Figure 5 in the direction indicated by the arrows;

Figure 5 is an end elevation of the igniter end of the fuse cartridge, and

Figure 6 is a longitudinal section through a modification of the fuse cartridge adapted to ignite trench mortar sheet powder at a distance of two inches at low temperatures.

Referring further to the drawings, the same numerals are used throughout the different figures to represent the same elements wherever applicable. In Figure 2, 10 represents generally the assembly of a trigger, trigger tripper, delayed action cartridge fuse and supporting structure. The latter comprises end plates 12 and 14 which

are spaced apart by posts 16, 18, 20 and 22. End plate 12 is threaded as at 13 for engagement with a tubular member such as gas-receiving tube 64. End plate 14 is bored centrally as at 15 to receive fuse cartridge 17 by threaded engagement

as at 19. Post 16 is slotted as at 21 to receive and pivotally support trigger 24 and tripper 26 at 23 and 25 respectively. Trigger 24 is biased toward end plate 14 by coiled spring 28 which is carried on pin 30 and held in biasing position by pin 32. Trigger 24 is provided with firing pin

34 which enters port 27 when trigger 24 is released by tripper 26. The latter is provided with a detent 29 which engages the free end of trigger 24. When the tripper is rotated a sufficient distance toward end plate 12, trigger 24 is released from engagement with detent 29 and spring 28 drives firing pin 34 through port 27 with force sufficient to detonate the primer in fuse cartridge 17. Tripper 26 is held in safety

position by pin 36 which is biased toward unlocked position by spring 38. Pin 36 and spring 38 are held in locked position by cotter pin 40 to which is freely attached ring 42. Pin 36, spring 38 and cotter pin 40 are housed or supported by bushing 44 which threadedly engages post 20 as

at 45 in alignment with channel 46. Bushing 44 is provided with a closure washer 47 which limits the throw of pin 36. Upon the withdrawal of cotter pin 40 from bushing 44 pin 36 is released from locking position by spring 38 and trigger 24 and trigger 26 are in firing position, i. e. trigger 26 is free to swing trigger 24 toward plate 12. Trigger 26 is actuated by trigger bar 48 which is longitudinally positioned exteriorly of post 20 and tube 64 and is supported by flat head screws 54 which extend through elongated slots the trigger bar and into threaded engagement with tube 64 as shown in Figure 1. The end of the trigger bar 48 toward plate 14 is off set as at 57 and is supported by bifurcated retaining plate 52 which is held in position by countersunk screw 53 which is threaded into engagement with end plate 14. This end of trigger bar 48 is slotted as at 67 to fit freely around the projecting end 50 of trigger 26. The other end of trigger bar is provided with a hook 55 of adequate stiffness to sustain a pull great enough to actuate the trigger but not so stiff that it does not bend out of the way when the ram pushes the device through the launching tube past the abutment on which hook 55 of the trigger bar impinges. Gas ducts 56 and 58 extend through end plates 12 and 14 and spacing posts 18 and 22 respectively, thereby providing egress for the apparatus gases generated by the combustion of material such as various types of powder, fuel etc. which preferably may be contained in fuel ignition chamber such as defined by fuel tube 60 as shown in Figure 2, and which threadedly engages end plate 14 as at 62. These apparatus gases passing through ducts 56 and 58 enter gas-receiving chamber 64 which is adapted to threadedly engage end plate 12 as at 66. The use of these apparatus gases forms no part of this invention, but they are used for different functions in the various types of devices launched from submarines.

Fuse cartridge 17, for reasons of economy, consists of two types; one is adapted to ignite black powder under the conditions stated above and the other is adapted to ignite trench mortar sheet powder under the conditions stated. This other type would ignite the black powder too, but it employs a larger volume of igniter mixture and hence is not used for this purpose.

Figures 3, 4 and 5 illustrate the first type of delayed action fuse. It consists of a cylindrical metallic body 17 comprising head portion 72, neck portion 74 and main body portion 76. The main body portion 76 is threaded as at 78 to engage end plate 14 as at 19. The cartridge is bored axially as at 71 to a shoulder 73 in neck 74. The bore is continued at a reduced diameter as at 75 and flares out into a cavity 77 in head 72. Body portion 76 is cut away as at 80 to provide opposite faces for the application of a wrench by means of which the cartridge is screwed home sufficiently in combination with copper cups 82 to form a gas tight seal. Body portion 76 is also chamfered as at 84 to streamline and to reduce the weight of the body. In the neck portion 74 a gas vent 86 is provided for the escape of gases developed when the primer is detonated.

The loading of this type of fuse cartridge comprises a percussion primer 88 of any well known type, a copper cup gasket 82, a column of gasless delay powder 92 consisting of 81-85% of barium peroxide and 19-15% of selenium to which may or may not be added 0-3% of French chalk

(talc), and an increment of 90-10 meal powder-magnesium as the igniter 94. The gasless delay powder is rammed and packed in the bore of the cartridge under a pressure of 8200 p. s. i. The igniter mixture is packed under a pressure of 4100 p. s. i. This loading is capable of igniting black powder over an air gap of twenty one inches in open air. The average delay time i. e. from the detonation of the primer to the spitting of the igniter mixture is 5.7 seconds.

The loading of the type of cartridge disclosed by Figure 6 is similar to that above except that volume of igniter mixture is enlarged by increasing the diameter and the depth and the proportion of black powder to magnesium is changed to 75-25. Maintaining the length of the column of gasless delay powder the same necessitates increasing the overall length of the cartridge by the amount of the increase in the depth of the igniter mixture. This loading ignites the trench mortar sheet powder at a distance of two inches in 5.7 seconds.

The preferred embodiment of the two types of fuses herein defined functions satisfactorily under the severe conditions set forth in the objectives, supra. It functions efficiently under water with the extreme temperature difference existing between that of the ignition gases passing through the ducts from the igniter chamber and to the operating chamber and that of the surrounding water. The device also functions under the objective conditions of internal and external pressure.

While the above specification has been drawn to a preferred embodiment of the invention it is not desired to be strictly limited thereto as other types of trigger tripping mechanism, other types of cartridges and loading and other housing structure could obviously be used. Such other types are within the spirit and scope of this invention to the extent as defined by the herewith appended claims.

What is claimed is:

1. In combination, in under water fuse actuated apparatus: a first tube defining a gas receiving chamber, a second tube defining a fuel igniting chamber; and a fuse assembly connecting said chambers in cooperating relationship; said assembly comprising: an axially bored metallic fuse cartridge; a percussion primer; a trigger arranged to detonate said primer; a tripper arranged to release said trigger; a trip bar arranged to actuate said tripper; said bar being mounted for longitudinal sliding engagement along the outer surface of one of said tubes; circular end plates engaging said tubes; a pair of aligned gas ducts in each of said plates; said plates being spaced apart by four posts positioned circumferentially at intervals of ninety degrees; one of said posts being adapted to pivotally support said trigger and said tripper; the opposite of said posts being adapted to guide the free end of said tripper into cooperating engagement with said bar; each of the other of said posts having gas ducts therein in respective alignment with said ducts in said plates.

2. The combination of claim 1 wherein said cartridge has a gas vent near its head portion, and wherein said primer is enclosed in a metallic sealing cup, and includes a rammed train of gasless delay powder consisting 81 to 85% barium peroxide, 15 to 19% selenium and a rammed ignition mixture; consisting of ninety parts meal powder and ten parts magnesium.

3. An under water fuse assembly adapted to inter-connect a pair of longitudinally aligned tubes; said assembly comprising: an axially bored metallic fuse cartridge; a percussion primer; a trigger arranged to detonate said primer; a tripper arranged to release said trigger; a trip bar arranged to actuate said tripper; said bar being adapted to be mounted for longitudinal sliding engagement along the outer surface of one of said tubes; circular end plates engaging said tubes; a pair of aligned gas ducts in each of said plates; said plates being spaced apart by four posts positioned circumferentially at intervals of ninety degrees; one of said posts being adapted to pivotally support said trigger and said tripper; the opposite of said posts being adapted to guide the free end of said tripper into cooperating engagement with said bar; each of the other of said posts having gas ducts there-

5
in in respective alignment with said ducts in said plates.
